UNITED STATES PATENT OFFICE

ASHER FLINT, AUGUST ZIMMERMAN, AND JACK G. LEO, OF NEW YORK, N. Y., ASSIGNEES TO FOX FILM CORPORATION, OF NEW YORK, N. Y., A CORPORATION OF NEW YORK

FILM PRINTING MACHINE

Application filed July 3, 1928. Serial No. 290,134.

This invention relates to continuous feed film printing machines in which a printed negative film has its subject matter duplicated photographically upon a sensitized blank positive film, juxtaposed and driven synchronously therewith.

In certain classes of films, used in picture projection apparatus, it is desirable to supply a lineal stripe of printed marks, in connection with the pictures, that when passing through a specialized type of projector, will reproduce sounds direct from the printed stripe, the same conveying audibly voices, music, etc., that have been imprinted on the film.

Such stripe of sound indications is preferably printed on the film along one of its marginal edges, interjacent the usual openings and picture portion and is quite narrow to avoid encroaching on the picture space.

It has hitherto been customary to make two separate exposures of the sensitized film, one to receive the pictorial subjects and the other the sound marks, each being independently printed at different times.

It is therefore an object of the present invention to provide a mechanism by which all the printing, that is the pictorial illustrations and sound stripe, is performed simultaneously at a single operation.

A further feature is in the provision of a device which may be readily attached to the common printer usually employed and which is fully complete in itself to perform the printing operation of the sound stripe tokens.

These advantageous objects are secured by the novel construction and combination of parts hereinafter described and shown in the accompanying drawings, forming an essential portion of this disclosure, and in which:

Figure 1 is a side elevational view of an embodiment of the invention, indicating its application.

Figure 2 is an enlarged fragmentary sectional view of the machine head and connected parts.

Figure 3 is a perspective view of the head in detail.

Figure 4 is a plan view of a piece of the film as printed.

Referring more in detail to the drawings, the supporting frame of the machine is designated by the numeral 10 on which is mounted a telescopic funnel 11 having a light-enclosing housing 12 at one end, the same being adjustably carried by rods 13 fixed in a bracket secured to the frame.

At the opposite, front end of the funnel 11, is an adapter ring 14 recessed at its rectangular front end to receive a hard felt insert 15 held in place by a plate 16.

A light-tight, hollow throat 17, provided with a removable cover at one side, is firmly held in the felt member 15 and is formed with flanges at its outer end curved to engage the wall of a cylinder 18 fixed therein, the cylinder having an opening 19 in register with the opening in the throat 17, the lower edge of the opening being approximately in the axial plane of the cylinder, and its upper edge substantially tangent to the bore, as seen in Figure 2.

Rotatably mounted on the ends of the cylinder 18 are plate sprockets 20 and 21 provided with teeth to engage the perforations A in the margins of a film B, (see Figure 4) the same bearing a series of closely adjacent pictures C and a stripe of sound indication D, when completed.

One of the cylinder sprockets 21 is provided with a hollow hub 22 having a flange to receive screws 23, by which the other sprocket 20 is secured, the sprockets being mounted so as to rotate in unison freely on the cylinder.

The cylinder 18 has another opening in the wall opposite the opening 19, in which is secured a block 24, having a narrow wedge-shaped aperture 25, substantially in register with the passage in the throat 17, this block having a curved peripheral surface extending slightly beyond the periphery of the cylinder in which it is set.

A negative or master film is delivered from a reel 26 supported by a post 27 on the frame 10 and a positive, sensitized blank film is disposed upon a mating reel 28 supported on an arm 29 reaching from the post 27.

The positive film is passed through a clean-

er, designated generically as 30, and thence under a guide roll 31, where it is brought into physical engagement with the negative film, which has been passed around tensioning rolls 32—32', carried on an arm 33 adjustably clamped to the post 27.

The guide roll 31 is rotatably mounted on the upper projecting end of a frame member 35, and the films passing under a pressure roll 36, are carried on a printing gate 37, pivoted at 38 to a lever 39 in turn pivoted to the frame member 35 at 40 and urged towards the cylinder 18 by a spring 41.

The roll 36 makes contact with the superposed films near the upper edge of the block 24, and the inner adjacent edge of the latch is in contact with the films throughout the length of the block, thus holding the films tensionally thereagainst as they pass the aperture 25, through which light rays pass from the lamp housing to cause a printing effect of the sound stripe.

The latch carried lever 39 is arranged to be moved outwardly, away from the cylinder, by a finger catch 42 at its upper end.

The positive film is separated from the negative by passing over rolls 43—44, while the negative film passes below the cylinder 18, around guide rolls 45—46—47 to be again brought into close relation with the negative film, and together they are carried past a printer 48 against which they are held by an aperture gate 49, these elements being well known.

From the printer the films pass over take-up sprockets 50, against which they are held by rolls 51—52 carried on a spring actuated lever 53 at the lower portion of the member 35, after which the films are wound upon take-up reels 54—55, respectively.

It will be understood the teeth of the sprockets 20—21 enter the perforations in both films so that relative movement is prevented, and that the sound record is printed simultaneously with the pictures, but at points slightly spaced apart along the length of the films, the sound record leading.

From the foregoing it will be seen that the invention resides in the incorporation with a continuous film printer of any standard type, of an attachment or built in mechanism whereby a sound stripe is produced, thus eliminating the necessity of a second, separate run of the films to obtain the same.

Although the foregoing is descriptive of the best known embodiment of the device, it will be apparent that minor changes in the shape and arrangement of parts may be made, such as may be indicated by good mechanical practice, without departing from the general scope and spirit of the claims hereto appended.

Having thus described our invention, what is claimed as new and desired to secure by Letters Patent, is:

1. The combination with a standard film printing machine, of a sound printing attachment comprising a separate and independent light housing, including a hollow cylindrical head having openings in its peripheral wall, a tubular connection between said housing and one of the wall openings, a block fixed in the other opening, said block containing an aperture registering with the first named wall opening, means to resiliently press moving films against said block to cover the aperture, and sprockets revoluble on the axis of said head to engage perforations in the margins of the films.

2. In combination with a machine to photographically print a blank film from a master film, said machine including feeding and tensioning means for the film, of an independent sound printing device comprising a lighting means adjustably secured to said machine, a telescopic funnel leading from the lighting means, said funnel having a section fixed on the machine, an adapter on the end of said section, said adapter having a rectangular recess in its outer face, a yieldable element secured in the recess, a hollow throat adjustably engaged in said element, a head fixed on said throat, said head having an aperture over which the films are passed to print a sound stripe, and means for resiliently maintaining the films in contact during their passage over the aperture, the aperture being in direct registration and open to said lighting means.

3. The combination with a standard film printing machine, of a sound stripe printing attachment comprising a hollow cylindrical head having opposed openings in a plane transverse and above its longitudinal center, a tubular throat of rectangular cross section fixed to said head in register with one of the openings, a yieldable support carried by the machine to adjustably receive the opposite end of said throat, said support registering with the lighting means of the machine, a lighting means, an apertured block fixed in the other opening of said head, and means for guiding a film when moving over the aperture in said block.

4. The combination with a standard film printing machine, of a sound stripe printing attachment comprising a hollow cylindrical head having opposed openings in a plane transverse and above its longitudinal center, a light house funnel, a socket carried on the end of said light house funnel, a hollow throat slidable in said socket, a felt insert therebetween, said throat being fixed on said head in register with one of the openings therein, a raised and apertured block fixed in the other opening, means to resiliently press passing films against the block over its aperture, and sprockets revolvably mounted on the ends of said cylindrical head to engage the marginal perforations in the films.

5. The combination with a standard film

printing machine, of a sound printing attachment comprising a separate and independent light housing, including a hollow cylindrical head having opposed openings in its peripheral wall in a plane transverse and offset from its longitudinal center whereby light rays pass directly through said head without obstruction, a tubular connection between said housing and one of the wall openings, a block fixed in the other opening, said block containing an aperture registering with the first named wall opening, means to resiliently press moving films against said block to cover the aperture, and sprockets revoluble on the axis of said head to engage perforations in the margins of the films.

In testimony whereof we have affixed our signatures.
